UNITED STATES PATENT OFFICE

WILBUR L. SIEGFREID, OF ATHENS, OHIO, ASSIGNOR TO THE MCBEE BINDER COMPANY,
OF ATHENS, OHIO, A CORPORATION OF OHIO

LOOSE LEAF BINDER

Application filed April 17, 1928. Serial No. 270,684.

My invention relates to the binding art and particularly to devices for receiving and filing loose sheets in a book form in which means are provided for the easy removal of a single sheet or a plurality of sheets without those remaining in the binder being separated or displaced from their order. My invention has for its principal object to produce such a device in a simple, strong, durable and easily accessible construction. My invention has for its further object to provide a quickly detachable sheet bar which can be removed carrying with it one or any desired number of sheets from those in the book without disturbing their order. My invention has for a further object to provide a simple means of binding the sheets in book form. My means of accomplishing the foregoing objects may be more readily understood by having reference to the accompanying drawings, in which—

Fig. 1 is an isometric perspective view of a binder equipped with my improvement;

Figs. 2 and 3 are perspective views showing the interior construction;

Fig. 4 is a detail view of the lock bar;

Fig. 5 is a detail view of one of the binder posts;

Fig. 6 is an isometric perspective view of the binder open, the extended position being shown in dotted lines;

Fig. 7 is a perspective view of the lock bar; and

Fig. 8 is an enlarged detail plan view of the lock bar in position.

My binder consists of lower and upper covers 10 and 15. The cover 10 is attached by means of a hinge 11 to an L-shaped member 12, the hinge being at the angle portion 40 of the L, as shown. The vertical portion of the L-shaped member is designed to slidably engage the vertical portion of a similar L-shaped member 13, also hinged, as shown at 14, to the upper cover 15, thereby forming a back for my binder, when the parts are joined, as hereinafter set forth.

To the inner surface of the short or horizontal side of the L-shaped member 12 I have secured a plurality of sheet receiving posts 16, these posts preferably being built

up of removable sections, as seen in Figure 5, one post being preferably located at the center of the said L-shaped member. The said posts are in perfect alinement and, are parallel to, and spaced from the vertical portion of the L-shaped member 12. 55

My detachable sheet bar 17 is removably positioned on the said L-shaped member 12, in the following manner: The sheet bar is provided near each end, with a downwardly projecting post, 18 and 19, respectively, exactly similar in every respect to the posts 16. On the upper side of the said sheet bar, preferably near each end, I have provided lugs, 20 and 21 which register with openings 25 and 26 formed in the horizontal portion of the upper L-shaped member 13. In the center of the sheet bar 17 I have provided an opening 22, to receive the end of the central post 16. To the upper end of the said central post 16 I have secured a headed lug 23, for purposes hereinafter set forth. 65

The shorter portion of the L-shaped member 13 is provided with orifices 24 and 25, which receive the lugs 20 and 21 and in the center thereof I have provided an orifice 26, to register with the orifice 22 to receive, and permit to pass therethrough, the headed lug 23. On the upper surface of the said shorter portion of the L-shaped member 13, I have mounted, for slidable movement, a lock bar 27, which has a bifurcated end the forks of which project, when moved inwardly, over a part of the opening 26 and enter the space under the head of the headed lug 23 and in this manner operate, to lock the parts of my binder together. 80

As the two L-shaped members are hinged at their angle portions to their respective covers, it is obvious the covers will lie flat on a table when my binder is opened, the shorter portions of the L-shaped members, projecting upwardly and holding the filed sheets between them. When the parts of my device are locked together the longer portion of one of the L-shaped members overlies and contacts the longer portion of its mating L-shaped member. 90

In practical operation the sheets to be filed are punched and threaded on the posts 100

16. The sheet bar 17 is then positioned, the posts 18 and 19 passing through prepared orifices in the sheets and their ends contacting the inner surface of the shorter portion of the L-shaped member 12, the headed lug, or stud, 23 projecting upwardly through the orifice 22. The upper cover is then placed in position, the lugs 20 and 21 engaging the orifices 24 and 25, respectively, and the headed lug 23 projecting through the orifice 26. The lock bar 27 is then pushed inwardly until its bifurcated end engages under the head of the headed lug 23, and the parts of my binder are securely locked together and firmly bind the filed sheets in the binder. When it is desired to remove or insert additional sheets, by sliding the lock bar 27 outwardly the forks of the bifurcated end disengage with the headed lug 23, when the upper cover 15 can be lifted as shown in the dotted lines in Fig. 6. This leaves the sheet bar 17 free and it can be removed for the purpose of adding additional sheets to the volume or if it is desired to remove a sheet or insert one or more in the central portion of the volume the sheet bar is lifted just enough to permit the desired sheets remaining on the posts 18 and 19 so that they cannot get out of order, while the remaining sheets will be held in place by the posts 16 and 23.

Having thus described my invention what I claim and desire to secure by Letters Patent of the United States is:

1. A loose leaf binder comprising upper and lower cover members, L-shaped members hinged to each of the cover members, said hinges being positioned at the angle of each L, the horizontal portion of the upper L having a plurality of orifices formed therein, a plurality of aligned vertical posts carried by the horizontal portion of the lower L and spaced from the vertical wall thereof, a sheet bar, vertical posts carried thereby and spaced differently from the first-mentioned posts, lugs formed upon the opposite side of the sheet bar adapted to engage in certain of said orifices of the upper L, said sheet bar having orifices formed therein for the reception of the ends of the posts carried by the lower L, one of said posts being of a length to extend through its corresponding orifice and through one of the said orifices formed in the upper L when the vertical walls of the L-shaped members are in overlapping relation, and a lock bar mounted upon the upper surface of the upper L for engagement with the said extended post.

2. A loose leaf binder, comprising upper and lower cover members, L-shaped members hinged to each of the covers at the angle of the L, each of the L's consisting of horizontal and vertical walls, orifices formed in the horizontal wall of the upper L, a plurality of spaced aligned vertical posts carried by the horizontal wall of the lower L, one of said

posts of greater length than the others, a sheet-binding bar, depending vertical posts carried thereby adapted to be positioned in spaced alignment with the first-named posts, lugs carried by the said sheet bar upon its side opposite to the side carrying the posts, the said lugs adapted to engage in certain of the orifices in the upper L, said sheet bar having orifices formed therein in alignment with the said posts of the lower L, the said post of greater length extending through the orifices of the sheet bar and upper L when the vertical walls of the L-shaped members are in overlapping relation, and a lock bar slidably mounted upon the upper surface of the upper L and adapted to engage the said extended post.

3. A loose leaf binder for binding sheets having preformed openings, comprising upper and lower covers, L-shaped members hinged to each of said covers at the angle of the L, posts on the lower one of said L-shaped members, one of which is centrally located, the end of said post projecting through an orifice in the upper L-shaped member, a head formed on the end of said central post, a sheet bar, said bar provided with an orifice therein which registers with said central post, posts carried by said sheet bar, said sheet bar provided with other orifices adapted to register with the other posts carried by the lower L-shaped member, a longitudinally movable lock bar carried upon the upper face of the upper L-shaped member to engage and lock the head of the said central post which projects through the orifice of said upper L-shaped member.

4. A loose leaf binder for binding sheets having preformed openings therein, comprising an upper cover and a lower cover, an L-shaped member hinged to each cover, the hinge being mounted at the angle portions of the L, there being a plurality of orifices in the horizontal portion of the upper L-shaped member, a central post which extends upwardly from the horizontal portion of the lower L-shaped member, a sheet bar, posts thereon to enter certain of the openings in the sheets to be bound, lugs in the opposite sides of said sheet bar which register with orifices adjacent the ends of the upper L, there being orifices in said sheet bar which register with a plurality of posts on said lower L aligned with said central post, a lock bar slidably longitudinally on the upper surface of the upper L, the end of said bar being bifurcated, the said central post being of such length as to extend above the upper surface of said upper L, and a head on said central post which is engaged by said bifurcated end when the lock bar is moved inwardly.

WILBUR L. SIEGFREID.
